UNITED STATES PATENT OFFICE.

BERNARD A. MALKIN, OF LACHINE, QUEBEC, CANADA.

DRIVE FOR PAPER-MAKING MACHINES.

Application filed April 19, 1926. Serial No. 103,106.

This invention relates to new and useful improvements in paper making machines and particularly to the driving mechanism therefor, and the object of the invention is 5 to provide a simple and economical driving mechanism which will be efficient in operation and so positioned that all parts thereof will be accessible for repairs and the like.

Another object is to provide a driving 10 mechanism of the class stated which will be compact in appearance and to one side of the mechanism.

In my invention I provide a main driving shaft, which extends from end to end of 15 the machine and adapted to positively drive a plurality of drier rolls, through the medium of suitable reductions of gearing; one set to each drier roll. The drier roll driving gear for each roll is mounted on auxiliary 20 shafts one to each roll and each auxiliary shaft is positively driven from the main driving shaft.

In the drawings which illustrate my invention—

25 Figure 1 is a partial side elevation of a paper making machine with tooth spur wheels and worm gears forming the driving mechanism between each drier roll and the main driving shaft.

30 Figure 2 is a partial end elevation of the mechanism shown in Figure 1.

Figure 3 is a partial side elevation of a paper making machine, with chain and sprocket mechanism and worm and worm 35 gears forming the driving mechanism between the drier roll and the main driving shaft.

Figure 4 is a partial end elevation of the mechanism shown in Figure 2.

40 Figure 5 is a partial side elevation of a paper making machine similar to that shown in Figure 1 with bevel tooth wheels, substituted for the worm gears.

Figure 6 is a partial end elevation of the 45 mechanism shown in Figure 5.

Figure 7 is a partial side elevation of a machine similar to that shown in Figure 5, with chain and sprocket mechanism substituted for the spur tooth wheel driving 50 mechanism.

Figure 8 is an end elevation of the device shown in Figure 7.

Referring more particularly to the drawings, 11 designates the upper drier rolls and 12 the lower drier rolls which are securely mounted on and adapted to rotate with the

drier roll spindles 13 and 14 respectively. The spindles 14 are rotatably mounted in suitable bearings 15 and spindles 13 are rotatably mounted in bearings 16, both sets 60 of bearings being secured to the main frame 17 of the machine by any suitable means and in such a manner that each upper roll is positioned between but spaced from the adjacent lower rolls. Guide rolls 18 and 19 are 65 mounted between the upper rolls and lower rolls respectively and may be rotatably mounted in bearings 20, secured to bracket or bearing 15 and in bearings 21 secured to the main frame of the machine. The 70 upper felt 22 passes over the uppermost side of the upper drier rolls and over the lowermost side of the guide rolls 18, while the lower felt 23 passes over the lowermost side of the lower drier rolls and over the uppermost side or face of the guide rolls. These 75 felts are of the endless type and are adapted to guide and hold the paper sheet 24 in its proper position as it passes from one end of the machine to the other. The travel 80 of the paper sheet is indicated by the arrow 25 and as will be seen passes first over one upper and then under one lower roll and between the felts and faces of the rolls and so on in this manner through the machine.

The drier roll spindles extend beyond the outer faces of the bearings at one side of the machine. The above mechanism is well known in this art and my improvement lies in providing suitable driving mechanism 90 which will efficiently drive the rolls. In Figures 1 to 4 respectively, I have shown worm wheels 26 secured to the drier roll spindles and driven by worms 27 formed integral with or secured to auxiliary shafts 95 28, rotatably mounted in suitable bearings 28^a, which may be secured to any fixed part of the machine. These auxiliary shafts are positioned at right angles to the roll spindles

having the longitudinal axes lying parallel 100 with the main driving shaft 29, which is also rotatably mounted in suitably fixed bearings 30 and extends from end to end of the machine. One auxiliary shaft is provided for each drier roll. The auxiliary 105 shafts may be driven from the main shaft by means of the toothed gear wheels 31 and 32, as shown in Figures 1 and 2, or they may be driven by means of the chain 33 and toothed sprocket wheels 34 and 35, as 110 shown in Figures 3 and 4. The worm and worm wheels may be provided with oil tight

gear cases 36, which may be partially filled with oil to form an easy means of lubricating the contacting or running surfaces of the gears. The spur toothed gear wheels 5 or the chain and toothed sprocket mechanism may be enclosed by oil tight casings 37. In Figures 5 to 7 respectively, bevel tooth wheels 38 are secured to the ends of each of the drier roll spindles and are 10 adapted to gear with the bevelled toothed pinions 39, secured to the auxiliary shafts 28^b, which are mounted on the machine in a somewhat similar manner to the similar shafts shown in Figures 1 to 4, and parallel 15 to the main driving shaft 29^a, which extends from end to end of the machine and is preferably positioned midway between the roll driving spindles with its longitudinal axes at right angles to the longitudinal axes of 20 the roll driving spindles. The driving connection between each of the auxiliary shafts and the main driving shaft may be through the medium of the spur tooth gear wheels 31^a and 32^a secured to the auxiliary shafts 25 and the main shaft respectively, as shown in Figures 5 and 6, or the driving means may consist of toothed sprocket wheels 34^a and 35^a the former secured to the auxiliary shafts and the latter to the main shaft with 30 endless chains 33^a connecting them together. The main driving shaft may be driven from a source not shown, but preferably at a point midway between its ends, so that the angular twist of the shaft while under operation may 35 be reduced to a minimum.

Modifications may be made in the construction and arrangement of the parts forming the driving mechanism without departing from the spirit of the invention.

40 In operation the main shaft is driven from a source, not shown, and simultaneously drives each of the auxiliary shafts which in turn drive a drier roll. The gearing or driving connection between the main shaft 45 and the auxiliary shafts are positive, that is toothed gearing or chains and tooth sprockets are used so that there is no slip between them. Positive gearing in the form of worm wheels or bevelled toothed pinions 50 and wheels are used between the auxiliary shafts and the roll driving spindles. The

arrangement of gears is simple and compact in appearance and lends itself to easy access for repairs and inspection.

Having thus described my invention, 55 what I claim is:—

1. In a drive for paper making machines having a plurality of drier rolls rotatably mounted on a frame, a main driving shaft having its longitudinal axis at right angles to the longitudinal axes of the drier rolls, a plurality of auxiliary shafts, one to each roll, and lying parallel with the main driving shaft, positive driving mechanism between the main driving shaft and each of the auxiliary shafts and positive driving mechanism between each auxiliary shaft and its adjacent drier roll. 60

2. In a drive for paper making machines having parallel rows of drier rolls, rotatably mounted in suitable framing, a main driving shaft positioned between the rolls and having its longitudinal axis at right angles to the axes of the drier rolls, a plurality of auxiliary driving shafts one for each drier roll and lying parallel with the main driving shaft, positive driving mechanism between the main driving shaft and each auxiliary shaft, and positive driving mechanism between the auxiliary shafts and their adjacent drier rolls. 70

3. In a driving mechanism for paper making machines having two parallel rows of drier rolls rotatably mounted in suitable framing members, a main driving shaft positioned between the rows of drier rolls and having its longitudinal axis at right angles to the longitudinal axes of the drier rolls, a plurality of auxiliary driving shafts rotatably mounted in suitable bearings and positioned in close proximity to the drier rolls and lying parallel to the main driving shaft, toothed gearing between the main driving shaft and the auxiliary shaft and positive driving mechanism between each auxiliary shaft and its adjacent drier roll. 90

4. In a driving mechanism according to claim 4, having toothed gearing between the auxiliary driving shafts and each drier roll. 95

In witness whereof, I have hereunto set 100 my hand.

BERNARD A. MALKIN.
